MOLD FOR TYPECASTING MACHINES

Gordon W. Curtiss, Atlanta, Ga.

Application June 7, 1952, Serial No. 292,283

3 Claims. (CL. 199—92)

1

This invention relates to an improved mold for a typecasting machine, and more particularly to an improved mold to permit such machines to cast larger type than has heretofore been possible with machines of this type such as that manufactured and sold by Lanston Monotype Machine Company, such machine being well known for many years by those skilled in the prior art. Representation of such a machine as to its basic construction and operation is to be found in U. S. Letters Patent No. 944,405, issued December 28, 1909, to J. S. Bancroft and M. C. Indahl. Improvements thereto are shown in subsequent Letters Patent, such as, for example, No. 1,193,346, issued August 1, 1916, to J. S. Bancroft and M. C. Indahl; and the machine is now so well known in its commercial form that no detailed description is deemed necessary.

The object of this invention is generally to increase the capacity of the mold for typecasting machines of the type mentioned, whereby type of abnormally wide dimension set-wise may be cast.

A particular object of my invention is to increase the capacity of the mold for typecasting machines of the character mentioned to the extent of three times the capacity of the commercial machines casting 8 pt. type.

Another object of my invention is to provide improved construction of the mold blade carrier and the mold blade carrier forward travel stop.

Another object of my invention is to provide improved mechanism for typecasting machines which is simple in design, rugged in construction, inexpensive to manufacture, and by means of which the casting capacity of the mold is increased up to threefold in machines of the class described.

Other and further objects and advantages of my invention will be apparent from the following description taken in conjunction with the accompanying drawings in which like characters of reference designate corresponding parts throughout the several views, and wherein:

Fig. 1 is a top plan view of a mold assembly embodying my invention.

Fig. 2 is a top plan view of the mold assembly shown in Fig. 1 with the shoe and guide removed.

Fig. 3 is a view similar to Fig. 2 but showing the mold in open position to form the casting cavity.

Fig. 4 is a right side view of the mechanism shown in Fig. 3.

Fig. 5 is a perspective view of a detail.

Fig. 6 is a bottom view of a detail.

In the embodiment chosen for purpose of illustration, certain of the machine parts shown being

of the construction well known in machines of the character set forth in the aforementioned patents, it will be sufficient to point out certain elements for purpose of identification, for example, the mold blade carrier 10, the top mold blade shoe 11, the mold blade guide 12, the lower mold blade 13, the upper mold blade 13', and the mold blade carrier latch spring 14. All of these parts are shown in Fig. 1, and they will be readily recognized by those skilled in the art.

Fig. 2 shows the mold assembly of Fig. 1 with the top mold blade shoe 11 and the mold blade guide 12 both removed to expose the mold blade carrier forward travel stop 15, the lower mold blade backward travel stop 16, and the small type block 17.

In prior art mechanisms, the mold blade carrier forward travel stop 15 was provided with an upper extension which passed through the customary opening 18 in the mold blade carrier latch and rested on the small type block 17; but this construction limited the extent to which the mold blade carrier could be moved, and therefore limited the casting cavity unnecessarily.

According to my invention, I have provided the mold blade carrier forward travel stop 15 with a short upper extension or portion 19 which terminates short of the mold blade carrier and the mold blade carrier latch, and is even shorter than the lower extension 19', and thereby provides ample clearance for the mold blade carrier latch 20 to be withdrawn with the mold blade carrier upon which it is mounted, without being obstructed by the upper extension 19 on the mold blade carrier forward travel stop. The function of the latch 20 is to disengage the lower mold blade from the top mold blade so as to cast low quads and spaces, but the function of this latch is well known and forms no part of the present invention, the latch being shown in the drawing merely as a usual part of a complete mold assembly.

In order to provide a positive forward travel stop action, I have added a lug 21 on the side of the mold blade carrier 10 upon which the mold blade carrier latch 20 is pivotally mounted. This lug 21 strikes against the upper extending portion 19 on the mold blade carrier forward travel stop 15 to limit the forward travel of the mold blade carrier, and these parts are ground for accuracy.

It will be understood by those skilled in the art that the function of the mold is to form a cavity of correct point and set sizes used in casting type, and the mold which forms a necessary part of the type casting machine is located in such position that when the matrix case (not shown)

3

descends in the normal operation of the machine the desired matrix or space is presented over the opening in the top of the mold to receive molten metal which passes into the mold cavity to form the face of desired type. Reciprocating movement is imparted to the mold blade carrier in the well understood operation of the machine to vary the size of the mold cavity set-wise, and to eject cast type from the mold.

In order to permit the mold blade carrier 10 to withdraw the mold blades sufficiently to form a casting cavity opening to at least .3321", it is also necessary to modify the lower mold blade backward travel stop or shoe 16 by cutting away a corner thereof as shown at 22 in Fig. 3. Also, the small type block 17 has been made wider to afford the longer mold wall necessary, and at the same time to afford a continuous bearing surface for the mold blades. It will be noted also that I have provided a similar cut-out portion, shown at 11' in Fig. 1, in the top mold blade shoe to accommodate the longer travel of the upper mold blade 13'; and the bottom opening 24 has been enlarged, as shown in Fig. 6.

By the above described construction in a mold for typecasting machines, I have provided means for increasing the casting cavity 25 up to .3321" and more, thus trebling the casting capacity of the commercial machine, or greatly increasing the casting capacity beyond anything possible with the commercial machine. It will be obvious to those skilled in the art that my invention provides needed mechanism of great usefulness, and that while I have illustrated and described my invention in a very practical embodiment thereof, various changes, adaptations and embodiments may be made without departing from the scope of my invention as defined in the following claims.

I claim:

1. Improvement in a typecasting machine mold having a slidably mounted mold blade carrier, upper and lower mold blades carried by said mold blade carrier, a mold blade carrier latch mounted on said mold blade carrier, and a mold blade carrier forward travel stop mounted adjacent said mold blade carrier, said improvement comprising

5 ing a lug on said mold blade carrier adjacent said mold blade carrier latch and extending from said mold blade carrier for engagement with a portion of said mold blade carrier forward travel stop to limit forward movement of said mold blade carrier, said portion of said mold blade carrier forward travel stop extending toward said mold blade carrier but terminating short of said mold blade carrier.

10 2. Improvement in a typecasting machine mold having a slidably mounted mold blade carrier, upper and lower mold blades carried by said mold blade carrier, a mold blade carrier latch mounted on said mold blade carrier, and a mold blade carrier forward travel stop mounted adjacent said mold blade carrier, said improvement comprising a lug on said mold blade carrier adjacent said mold blade carrier latch and extending from said mold blade carrier for engagement with a portion of said mold blade carrier forward travel stop to limit forward movement of said mold blade carrier, said portion of said mold blade carrier forward travel stop extending toward said mold blade carrier but terminating short of said mold blade carrier and said mold blade carrier latch.

15 3. Improvement in a typecasting machine mold having a slidably mounted mold blade carrier, upper and lower mold blades carried by said mold blade carrier, a mold blade carrier latch pivotally mounted on one side of said mold blade carrier, and a mold blade carrier forward travel stop mounted adjacent the side of said mold blade carrier on which said mold blade carrier is mounted, said improvement comprising a lug on said mold blade carrier adjacent said mold blade carrier latch and extending from said mold blade carrier for engagement with a portion of said mold blade carrier forward travel stop to limit forward movement of said mold blade carrier, said portion of said mold blade carrier forward travel stop extending toward said mold blade carrier but terminating short of said mold blade carrier and said mold blade carrier latch.

GORDON W. CURTISS.
